DOORSTOP

Serge W. Cheremeteff, Canaan, N. H.

Application April 15, 1942, Serial No. 439,131

3 Claims. (Cl. 292—124)

My invention relates to door stops and has particular reference to devices for holding doors or other objects in a fixed position.

My invention has for its object to provide a device for holding a door in an open position, the device being adapted to be fastened to a stationary object such as floor or wall and having a movable hook-shaped member with a spring urging the member into an operative or locking position. The hook-shaped member has a cam-shaped outer portion adapted to be engaged by the edge of the door when the latter is moved into the open position, the pressure of the door against the cam portion of the member causing the latter to recede and to admit the door to the other side of the hook where the door is stopped by a resilient projection on the device. The spring brings the member back into the operative position, locking the door in the open position.

In order to reduce the shock and jar when the door strikes the member, the cam-shaped portion is so designed that the initial shock is materially reduced and the force exerted by the door against the member remains substantially constant while the member is gradually accelerated in its receding movement. My device is therefore applicable to doors in buildings, automobiles, airplanes, boats, etc.

Another object of my invention is to provide a door stopping and locking device in which the locking member or bar is pivoted for rotation in a horizontal plane, a pedal being provided for movement in a plane at an angle to the plane of the locking member, preferably at right angles thereto, so that the pedal can be conveniently depressed by a foot when it is desired to release the door.

My invention is more fully described in the accompanying specification and drawing, in which:

Fig. 1 is a top plan view of my device partly in section;

Fig. 2 is a sectional elevational view of the same;

Fig. 3 is a side view of a modified device;

Fig. 4 is a plan view of another modification;

Fig. 5 is a diagrammatic view of the curvature of the cam-shaped portion of the movable member.

My door stop, as shown in Figs. 1 and 2, consists of a frame or housing 1 with flanges or feet 2 for attaching the same to a stationary object, such as a floor indicated by a line 11, Figs. 2 and 3. A locking bar 3 is pivotally supported

in the frame at 4 for rotation in a horizontal plane. The bar has a hook 5 for engaging the side of a door 6, a resilient bumper 7 being provided at the other side of the frame for stopping the door when it is moved past the hook 5. A spring 8 urges the hook against the door.

The outer end of the member 3 has a cam-shaped portion 9 which is slidably engaged by the edge of the door when the latter is moved against the bar, thereby depressing the bar and permitting the door to pass beyond the hook 5. The portion 9 is preferably of a concave shape in order to reduce the first shock when the door is rapidly moved against the bar, the first angle α' (Fig. 5) being relatively small. The angles α of the tangents to the curve are gradually increased toward the base of the curve in order to gradually increase the rate of movement of the bar as it is accelerated by the pressure from the door.

I have found that the least total resistance is obtained when the force applied to the hook by the door is substantially constant, the resistance (considering the acceleration) being also constant. The curvature of the hook is therefore so selected as to reduce the shock when it is struck by the edge of the door, being preferably of a parabolic type with progressively increasing angles of its tangents.

The housing has a slot 10 at the side for the bar 3. The bar has an opening 26 for a lever 13 which is pivoted at 14 at the bottom of the frame and moves in a slot in the frame. The upper end of the lever has a pedal 15 to be engaged by a foot when it is desired to move the bar 3 back for releasing the door. The lever 13 has a cam-shaped side 16 slidably engaging the bar 3 in the opening 26 when the pedal is depressed.

A modified device is shown in Fig. 3, the frame 16 having flanges 17 for attaching it to a wall 26 back of the door. The mechanism of this device is otherwise the same as shown in Fig. 1.

Another modification is shown in Fig. 4, especially suitable for locking the door in a closed position, as applied, for instance, to automobiles, etc. A bar 18 slides in a frame 19 fitted in a door jamb 20. A spring 21 urges the bar or bolt 18 outward, a rod 22 in a slot 23 limiting the outward movement. The bolt is depressed by the movement of the door 6 until the door is closed, the bar 18 entering a slot 24 in the door and locking the latter. A handle 25 is provided for withdrawing the bar or bolt 18.

It is understood that my door stop may be

further modified without departing from the spirit of my invention, as set forth in the appended claims.

I claim as my invention:

1. A door stop comprising a box-shaped frame adapted to be attached to a stationary object; a bar pivotally supported in the frame on a substantially vertical axis, the outer end of the bar having a hook extending outside the frame for engaging the edge of the door, the outer side of the hook having a cam-shaped surface adapted to be slidably engaged by the door when the latter is moved over the hook, thereby retracting the bar; yieldable means to urge the hook into an operative position for engaging the door; and a vertically movable, manually operable pedal slidably engaging the bar for moving the bar away from the door.

2. A door stop comprising a box-shaped frame adapted to be attached to a stationary object; a bar pivotally supported in the frame on a substantially vertical axis, the outer end of the bar having a hook extending outside the frame for engaging the edge of the door, the outer side of the hook having a cam-shaped surface adapted to be slidably engaged by the door when the

latter is moved over the hook, thereby retracting the bar; yieldable means to urge the hook into an operative position for engaging the door; and a pedal pivotally supported in the frame having a cam-shaped side slidably engaging the bar, the pedal being adapted to be depressed in direction transverse to the plane of the bar for moving the bar away from the door for releasing the latter.

3. A door stop comprising a frame adapted to be attached to a stationary object; a bar pivotally supported in the frame on a substantially vertical axis, the outer end of the bar having a hook for engaging the edge of the door, the outer side of the hook having a cam-shaped surface adapted to be slidably engaged by the door when the latter is moved over the hook, thereby retracting the bar; yieldable means to urge the hook into an operative position for engaging the door, the bar having an opening; and a pedal pivotally supported in the frame on a substantially horizontal axis and passing through the opening, the pedal, when depressed, being adapted to move the bar away from the door in a plane at right angles to plane of the pedal.

SERGE W. CHEREMETEFF.
